UNITED STATES PATENT OFFICE.

ARTHUR MIDDLETON ROSE, OF YONKERS, NEW YORK, ASSIGNOR TO
MATTHEW J. WHITTALL, OF WORCESTER, MASSACHUSETTS.

DESIGN FOR CARPET-BORDER.

SPECIFICATION forming part of Design No. 24,008, dated February 5, 1895.

Original application filed December 15, 1894, Serial No. 531,981. Divided and this application filed January 7, 1895. Serial No. 534,163. Term of patent 3½ years.

To all whom it may concern:

Be it known that I, ARTHUR MIDDLETON ROSE, a citizen of the United States, residing at Yonkers, in the county of Westchester and State of New York, have invented and produced a new and original Design for a Carpet-Border, of which the following is a specification.

This application is a division of an application filed by me December 15, 1894, Serial No. 531,981, wherein I have claimed the combination of the border claimed in this application with a carpet body.

My invention relates to a design to be worked into or upon carpet borders and similar fabrics, and it consists of the novel features and arrangements as herein described and claimed, and shown in the accompanying drawing, which forms part of this specification.

The said drawing is a face view of a carpet border illustrating my new design.

The border consists essentially of a ground-work or back-ground and a longitudinal figure, which extends substantially parallel with the sides of the border, said figure being ar-

ranged so as to leave a considerable section or panel of the groundwork or back-ground exposed upon each side thereof.

As shown in the drawing, C designates the longitudinally extending figure. This part of the design consists of a longitudinally extending conventionalized figure, spray or vine, which will harmonize with the body of the carpet in connection with which the border is to be used. This longitudinally extending figure is arranged on the border so as to leave panels or spaces A and B of the groundwork or back-ground between each side of the longitudinally extending figure and the sides of the border.

What I claim as new, and desire to secure by Letters Patent, is—

The design for a carpet border substantially as herein shown and described.

In testimony whereof I have hereunto set my hand in the presence of two subscribing witnesses.

ARTHUR MIDDLETON ROSE.
